UNITED STATES PATENT OFFICE.

HERMINE GUIDEZ, OF NEW YORK, N. Y.

DESIGN FOR A PATTERN FOR DRESS-SKIRTS.

SPECIFICATION forming part of Design No. 35,844, dated April 1, 1902.

Application filed February 26, 1902. Serial No. 95,825. Term of patent 3½ years.

To all whom it may concern:

Be it known that I, HERMINE GUIDEZ, a citizen of the United States, residing in New York, borough of Manhattan, and State of New York, have invented and produced a new and original Design for Patterns for Dress-Skirts, of which the following is a specification, reference being had to the accompanying drawings, forming a part thereof, in which—

- Figure 1 is a side elevation of a dress-skirt pattern, showing my new design; and Fig. 2 is a horizontal section of the same on line 2 2, Fig. 1.

As shown in the drawings, *a* represents the skirt-body, *a'* the girdle-piece, and *b* the side-gore trimmings, which extend from the girdle-piece in downward direction to the lower part of the skirt. The side-gore trimmings *b* are connected at several points between the girdle-piece and the bottom of the skirt by festoon-like bands *b'*, which form, in connection with the side-gore trimmings, the leading features of the design. The girdle-piece,

side-gore trimmings, and curved bands are ornamented by beaded edge trimmings, and 25 the side-gore trimmings, adjacent their points of connection with the girdle-piece and transverse bands, with diamond-shaped openings *b*². The lower set of curved bands is arranged with two openings *b*², which partly overlap 30 each other. The bottom of the skirt *a* terminates in flounces *d*, trimmed with beads in the same manner as the side-gore trimmings.

Having thus described my invention, what I claim as new, and desire to secure by Letters 35 Patent, is—

The design for a pattern for dress-skirts, as herein shown and described.

In testimony that I claim the foregoing as my invention I have signed my name in presence of two subscribing witnesses. 40

HERMINE GUIDEZ.
